DESIGN.

A. L. & D. M. KITSELMAN.
PATTERN FOR WIRE FENCES.

A technical line drawing of a diamond-shaped mesh structure, likely a patent illustration. The structure is composed of a grid of vertical and horizontal lines representing ropes or cords. The intersections of these lines form a series of diamond-shaped cells. Some of these cells are highlighted with diagonal lines. Various numbers are used to label specific parts of the structure: '1' is at the top center; '2' is on the right side, appearing in several locations; '3' is on the left side, appearing in several locations; '4' is at the bottom center; '5' is in the middle right; '6' is in the middle left; and '7' is on the far right. The drawing is enclosed in a rectangular border.

UNITED STATES PATENT OFFICE.

ALVA L. KITSELMAN AND DAVIS M. KITSELMAN, OF RIDGEVILLE, INDIANA.

DESIGN FOR A PATTERN FOR WIRE FENCES.

SPECIFICATION forming part of Design No. 25,333, dated March 31, 1896.

Application filed October 8, 1895. Serial No. 565,085. Term of patent 7 years.

To all whom it may concern:

Be it known that we, ALVA L. KITSELMAN and DAVIS M. KITSELMAN, citizens of the United States, residing at Ridgeville, in the 5 county of Randolph and State of Indiana, have invented a new and original Design for Wire-Fence Patterns, of which the following is a specification.

This invention relates to a new and original 10 design for a wire-fence pattern; and it has for its object to provide a design of this character that shall be both useful and ornamental.

The leading feature of the design resides in a wire-fence pattern having a series of horizontal twisted cables, a series of twisted-wire pickets interwoven with the cables and intertwined with each other to form in the spaces between the intermediate and the uppermost and lowermost cables diamond-shaped figures, and vertically-alined 15 reversely-disposed triangularly-shaped figures arranged between each pair of diamond-shaped figures, and in the central space between the intermediate cables to form a horizontal series of disconnected diamond-shaped figures, and hour-glass-shaped figures between each pair of said diamond-shaped figures. The leading feature of the design is completed by a series of vertical straight lines intersecting with all of 20 the cables except the uppermost cable and arranged to vertically bisect the diamond-shaped figures in the central space and the similarly-shaped figures in the space below 25 the central space.

30 In the drawing the figure represents an elevation or plan view of a section of ornamental

fence-pattern embodying the herein-described design.

In the drawing the numeral 1 designates horizontal twisted-wire cables arranged parallel with each other and forming longitudinal spaces therebetween. A series of twisted pickets 2 are interwoven with the cables 1 and are intertwined with each other to form in the spaces confined between the intermediate and the uppermost and lowermost cables diamond-shaped figures 3 and vertically-alined reversely-disposed triangularly-shaped figures 4 arranged between each pair of the figures 3. In the central space between the 40 intermediate cables 1 the arrangement of the pickets form a horizontal series of disconnected diamond-shaped figures 5 and hour-glass-shaped figures 6 between each pair of said figures 5. The design is completed by a 45 series of vertical twisted wires 7, which form straight lines intersecting all of the cables excepting the uppermost cable and vertically bisecting the diamond-shaped figures 5 and the similarly-shaped figures directly there- 50 below.

What we claim is—

The design for a wire-fence pattern herein shown and described.

In testimony that we claim the foregoing as 65 our own we have hereto affixed our signatures in the presence of two witnesses.

ALVA L. KITSELMAN.
DAVIS M. KITSELMAN.
